LIQUID-BREAK CIRCUIT INTERRUPTER

Robert E. Friedrich and Carl G. Lentjes, Pittsburgh, Pa., assignors to Westinghouse Electric Corporation, East Pittsburgh, Pa., a corporation of Pennsylvania

Application April 28, 1950, Serial No. 158,892

5 Claims. (Cl. 200—150)

1

This invention relates to circuit interrupters, in general, and more particularly to arc-extinguishing structures therefor of the liquid-break type.

A general object of our invention is to provide an improved piston construction for a circuit interrupter of the liquid-break type.

Another object is to provide an improved piston construction for a circuit interrupter of the type establishing a pressure-generating break and a serially related interrupting break.

A more specific object is to provide an improved piston construction for a liquid-break type of circuit interrupter in which the piston is at least partly of the circulating type, and providing the location of the piston arrangement in such relation to the pressure-generating gap that a minimum length of liquid flow travel is involved.

Still another object is to provide a circuit interrupter having an improved piston construction in which the piston is not only of the circulating type with the arc-generating pressure substantially balanced thereon, but the piston has means for causing in addition to the circulating flow, a positive diminution of liquid within the piston chamber to thereby effect a positive sending of fluid through passages into the pressure break and along toward the interrupting break to pass out of the interrupter.

Further objects will be readily apparent upon reading the following specification taken in conjunction with the drawings, in which:

Figure 1 is a side elevational view, partially in vertical section, of a circuit interrupter embodying our invention and shown in the closed circuit position;

Fig. 2 is an enlarged vertical sectional view through the left-hand arc-extinguishing unit of the interrupter shown in Fig. 1, with the contact structure being illustrated in the closed circuit position;

Fig. 3 is a fragmentary vertical sectional view taken along the line III—III of Fig. 2;

Fig. 4 is a view similar to that of Fig. 2, but showing the disposition and arrangement of the parts at an intermediate point in the opening operation; and

Fig. 5 is a fragmentary vertical sectional view taken along the line V—V of Fig. 4.

Referring to the drawings, and more particularly to Fig. 1 thereof, the reference numeral 1 designates a tank filled to the level 2 with a suitable arc-extinguishing fluid 3, in this instance circuit breaker oil. Depending from the

2

cover 4 of the tank 1 are a pair of terminal bushings 5, 6 to the lower ends of which are secured arc-extinguishing units, generally designated by the reference numeral 7 and electrically interconnected, in the closed circuit position shown, by a conducting cross-bar 8. The cross-bar 8 is actuated reciprocally in a vertical direction by an insulating operating rod 9.

Referring to Figs. 2 and 4, which more clearly show the internal construction of the arc-extinguishing unit 7, it will be noted that clamped to the lower end of the terminal stud 10 is a clamp 11 which is bolted by bolts 12 to a top dome casting 13. Movable within the top dome casting 13 interiorly thereof is a rotatable pressure-generating contact 14. In the closed circuit position, shown in Fig. 2, the pressure-generating contact 14 engages an intermediate contact 15, the latter in turn engaging a lower interrupting rod-shaped contact 16 secured to the extremity of the cross-bar 8.

During the opening operation, the rotatable pressure-generating contact 14 separates upwardly away from the intermediate contact 15 to establish therebetween a pressure-generating arc 17 more clearly shown in Fig. 4. Also, an interrupting arc 18 is established between the intermediate contact 15 and the lower movable interrupting contact 16. These two breaks are established practically simultaneously.

An insulating operating rod 19 is provided movable longitudinally of the unit 7, laterally thereof. The lower end of the operating rod 19 abuts against the cross-bar 8 and is forced by the latter upwardly during the closing operation against the biasing action exerted by an accelerating compression spring 20 disposed at the upper end of the operating rod 19. The compression spring 20 seats at its upper end against the bight portion 21 of a bracket 22, the latter forming an integral part of an apertured cap 23. The cap 23 is secured by any suitable means, such as by welding, to the top dome casting 13.

The pressure-generating contact 14 is rotatable, being pivotally mounted on a fixed removable pivot pin 24, the outer ends of which are journaled in the side walls of the top dome casting 13. The right-hand end of the rotatable pressure-generating contact 14 is bifurcated, and, referring to Fig. 3, the legs 25 of the right-hand forked end of the pressure-generating contact 14 have open slots 26 formed therein. Within the open slots 26 disposed at the extreme right-hand ends of the legs 25 of the pressure-generating contact 14 are bosses 27, the latter forming an integral

part of a sleeve 28. The sleeve 28 slidably surrounds the operating rod 19 and has its upper end threadedly secured at 29 to an apertured cup-shaped member 30. Disposed within the cup-shaped member 30 is a compression spring 31 which serves to provide the requisite contact pressure between the several contacts 14, 15, and 16. In other words, a shoulder 32 is formed upon the operating rod 19 which supports a washer 33 near the end of the closing stroke engaging the compression spring 31 as shown in Fig. 2. During the closing operation, after the contacts 14, 15 and 16 have made contacting engagement, the operating rod 19 may continue slightly upwardly in its closing motion to thereby slightly compress the compression spring 31. Thus, the compression spring 31 forms the contact pressure for the several contacts.

A piston chamber 34 is formed integrally with the top dome casting 13. A piston 35 of the circulating type is disposed within the piston chamber 34, and has its lower or working face 36 operative to force liquid downwardly in the direction of the arrows 37 (Figs. 2 and 3) through a passage means 38 interconnecting the piston chamber 34 with the pressure-generating arc 17. Fig. 3 more clearly shows that the lower end of the piston chamber 34 is expanded, as at 39, forming two conduits to register with openings 40 in the plate structure. The openings 40 communicate with a passage 41 which, at its left-hand end, communicates radially, as at 42, with an orifice 43, through which the pressure-generating arc 17 is drawn by cooperation of the pressure-generating and intermediate contacts 14 and 15.

The pressure-generating chamber, generally designated by the reference numeral 44, and essentially defined by the top dome casting 13, communicates by a plurality of, in this instance three, passages 45 with two vertical flow passages, generally designated by the reference numeral 46, the latter in turn communicating with a plurality of pairs of inlet passages 47. The inlet passages 47 lead to a plurality of orifices 48, through which the interrupting arc 18 is drawn by cooperation of the intermediate and interrupting contacts 15, 16. On the opposite sides of the orifices 48 from the inlet passages 47 are disposed vent passages 49, which lead directly out of the unit 7 in a direction perpendicular to the plane of the drawings. The interrupting chamber 50 has a configuration more clearly set forth in U. S. Patents 2,406,469 and 2,467,760; issued to Leon R. Ludwig, Benjamin P. Baker and Winthrop M. Leeds, and assigned to the assignee of the instant application. Consequently, reference may be had to these two patents for details of the interrupting structure 50, and since the present invention is not concerned with those details only a cursory description of the plate structure is here presented.

The upper end of the insulating operating rod 19 has forced thereupon a metallic end portion 51 having a shoulder 52 upon which seats a washer 53. The washer 53 is slidable upon the end portion 51. Seated upon the washer 53 is a compression spring 54, the upper end of which seats against an inturned flange 55 forming the upper end of a tubular member 56. The side walls of the tubular member 56 have vertical slots 57 (Fig. 3) formed therein permitting a communication between the region 58 and the passage means 38. The lower end of the cylindrical member 56 has an outturned flange 59 which rests

about the opening 60 formed at the lower end of the piston chamber 34.

The compression spring 54 has, as one of its purposes, the maintenance of the cylindrical member 56 within the opening 60 in a stationary position. Another function of the compression spring 54 is to initially help the spring 20 in moving the rod 19 downwardly. Also the spring 54 moves the pressure contact 14 to the open circuit position, as shown in Fig. 4.

A cylindrical extension 62, upon which the adjustable nuts 61 are threaded, has a lower protruding end 64 inserted by a press fit within the upper cylindrical portion 65 of the end 51 of the operating rod 19. A locking pin 66 is inserted, and a set screw 63 locks the locking pin 66 in a set position. The cylindrical extension 62 may also serve as a housing for the compression spring 20.

It will be observed that the circulating piston 35 has an upwardly extending cylindrical portion, or member of enlarged cross-sectional area 67 movable therewith, the latter having an inturned flange 68 integrally formed therewith. During the opening operation, the nuts 61 engage the flange 68 at the upper end of the piston 35 with a delayed action. Consequently, there is a lost-motion connection 69 between the operating rod 19 and the circulating piston 35. It will also be noticed that the cylindrical extension 62 has a shoulder 70 formed thereupon, which picks up the flange 68 of the piston 35 during the closing operation. A relatively light compression spring 71, seated between the piston 35 and the cap 23, serves to bias the piston 35 downwardly so that the flange 68 is constantly seated against the shoulder 70 in the closed circuit position of the interrupter. As a result of this construction, there is always the same amount of desired time lag associated with the lost-motion connection 69 before the nuts 61 pick-up the flange 68, and hence the piston 35, and carry the latter downwardly therewith.

Associated with the pressure-generating chamber 44 is an overpressure valve 72 and a normally open gas relief valve 73. It will be observed that the pin 24, upon which the pressure-generating contact 14 is rotatably mounted, may be removed out of the casting 13 so as to permit the pressure-generating contact 14 to be removed out of the pressure-generating chamber 44 through the side opening 74 following removal of the side plate 75 and after detachment of the shunt lead 76 from its bolted connection at 77 to the casting 13.

The operation of our improved interrupter will now be described. In the closed circuit position of the interrupter, shown in Figs. 1, 2 and 3, the electrical circuit extending therethrough includes terminal stud 10, conducting clamp 11, conducting casting 13, flexible shunt 76, pressure-generating contact 14, intermediate contact 15, lower movable interrupting contact 16, and through the conducting cross-bar 8 to the right-hand arc-extinguishing unit 7. The electrical circuit extends in a similar manner through the right-hand arc-extinguishing unit 7 to the right-hand terminal stud of the interrupter.

During the opening operation, either in response to manual operation, or in response to overload conditions existing in the circuit controlled by the interrupter, suitable mechanism, not shown, is operative to cause downward opening motion of the insulating lift rod 9.

The downward opening motion of the lift rod

9 causes corresponding downward opening movement of the cross-bar 8 and both interrupting contacts 16 at its opposite extremities. Considering only one unit 7, it will be apparent that downward motion of the cross-bar 8 and movable interrupting contact 16 permits the accelerating compression spring 20 to force the operating rod 19 downwardly so that the lower end thereof maintains contact with the cross-bar 8. Spring 54 serves initially to accelerate rod 19, and may continue to do so during the remainder of the opening stroke of the pressure-generating contact 14. The contacts 14, 15 and 16 remain in engagement due to the compression of the compression spring 31 until the washer 53 strikes the top of the cup-shaped member 30. By this time, the compression spring 31 is only slightly stressed, and the sleeve 28 then moves downwardly solely under the biasing action exerted by spring 54.

Since the bosses 27 are integrally formed with the sleeve 28, the bosses 27 move downwardly carrying the legs 25 therewith, and thus rotating the pressure-generating contact 14 about its pivot 24 drawing a pressure arc 17. Substantially simultaneously with the separation of the contacts 14, 15, the contact 16 separates from the contact 15 to establish an interrupting arc 18, more clearly shown in Fig. 4. As a result, there is a practically simultaneous formation of a pressure-generating arc 17 and an interrupting arc 18. The pressure-generating arc 17 reacts upon the oil disposed within the pressure-generating chamber 44 to form gas under pressure. This pressure forces oil downwardly through the passages 45 into the vertical flow passages 46, through the inlet passages 47, into engagement with the interrupting arc 18 and through the orifices 48 to exhaust out of the unit 7 through the laterally disposed vent passages 49.

Because of the provision of a lost motion connection 69 between the operating rod 19 and the circulating piston 35, there is delayed pumping of oil through the passages 38, 40 and 42 into the pressure-generating arc 17. This delayed pumping brought about by the provision of the lost-motion connection 69 has the advantage that the time delay may be such as to fall within the teachings of United States Patent 2,592,635, issued April 15, 1952. As set forth in this patent, such a time delay greatly assists in bringing about charging current interruptions.

When the operating rod 19 has traveled downwardly far enough so that the nuts 61 do engage the flange 68, the circulating piston 35 will, at this time, be under the biasing action exerted by the accelerating compression spring 20. This downward biasing action exerted by the compression spring 20 will be slightly assisted by the relatively light compression spring 71, which normally maintains the flange 68 against the shoulder 70 in the closed circuit position to bring about the desired time delay.

Even though rotation of pressure contact 14 may be halted by sleeve 28 striking the stop 83, the rod 19 continues to move downwardly under biasing action exerted by compression spring 20.

It will be observed that the circulating piston 35 has its lower or working face 36 exposed to the arcing pressure through the passage means 38, passages 40, passages 41 to the pressure-generating arc 17. It will also be observed that the top or non-working face 79 of the circulating piston 35, of annular area "C" (Fig. 4), is also 75

exposed to the arcing pressure by virtue of an opening 80 provided in the piston chamber 34. Since, therefore, arcing pressure acts on both sides 36, 79 of the circulating piston 35, the pressure of the springs 20 and 71 need be such only as to overcome liquid friction through the passages. Since the entire piston assembly is disposed near to the pressure-generating arc 17, the length of the passages is short, and liquid friction through these passages is held to a minimum.

In addition to the circulating oil flow of annular area "C" caused by operation of the circulating piston 35, it will be observed that a cross-sectional area "A," or cross-sectional area of the operating rod 19 moves out of the piston chamber 34. Also, it will be observed that an enlarged cross-sectional area "B" or cross-sectional area of the cylindrical portion 67 of piston 35 moves into the piston chamber 34, so that, in addition to the circulating flow, there is a positive diminution or lessening of liquid volume within the piston chamber 34 to thereby bring about a positive displacement of liquid out of the piston chamber 34 through the passages 38, 40 and 41 into the pressure-generating arc 17, and onwardly through the passages 45, 46, 47 and 49 out of the arc-extinguishing unit 7.

Thus, we have provided two types of flow resulting from the operation of our improved piston assembly. The first type of flow of annular area "C" is a circulating oil flow through the pressure-generating arc 17 and back to the piston 35. However, the second type of flow is a positive displacement of liquid out of the piston chamber 34, and hence this type of flow results in a complete displacement of liquid out of the arc-extinguishing unit 7. It is equivalent to a piston of area B—A forced into the piston chamber 34 or forced into the unit 7 to result in the displacement of oil out of the unit 7. In other words, this second type of flow, the displacement type, sends a liquid flow sequentially through the pressure-generating arc 17 and onwardly into the interrupting arc 18, and thence out of the interrupting unit 7 through the vent passages 49.

During the opening operation, the gas relief valve 73 closes, as shown in Fig. 4, and under excessive pressure, the valve 72 will open. In the closed position of the interrupter, the gas relief valve 73 opens, upon a subsidence of pressure within the pressure-generating chamber 44 to permit an exit of gas out of the pressure-generating chamber 44 through the gas relief valve 73.

During the closing operation, the lift rod 9 and cross-bar 8 move upwardly, picking up the operating rod 19 to move the latter upwardly. The upward motion of the operating rod 19 continues until the several contacts 14, 15 and 16 make engagement, at which time further continued upward movement of the operating rod 19 effects a compression of the contact compression spring 31 to thereby effect the requisite contact pressure between the several contacts. During the upward motion, the shoulder 70 on the operating rod 19 has picked up the piston 35 and charged it, the compression spring 71 maintaining the flange 68 against the shoulder 70. Furthermore, the shoulder 52 on rod 19 picks up the slidible washer 53 and compresses the spring 54, thereby ensuring that the cylinder 56 is maintained within the opening 60 of piston chamber

34 with the flange 59 thereof against the lower face 81 of the piston chamber 34.

From the foregoing description of our improved interrupter, it will be apparent that we have provided an improved piston construction for a liquid break type of circuit interrupter, particularly one establishing a pressure-generating arc and a serially related interrupting arc. It will be observed that we have not only provided a circulating flow, thereby reducing the spring pressures involved since arcing pressure acts on both sides of the circulating piston 35, but also, in addition to the circulating flow, we have provided a positive displacement or diminution of liquid volume within the piston chamber 34 to actually displace liquid out of the unit 7. This latter positive forced liquid flow is sent sequentially through the pressure-generating arc 17 and onwardly through the interrupting arc 18 and out of the unit 7.

From the foregoing, it will, therefore, be apparent that we have provided two types of flow, a circulating flow especially effecting interruption of the pressure-generating arc 17, and a net displacement or lessening of liquid volume within the piston chamber 34 to effect interruption of the interrupting arc 18, since such a type of flow directly effects both arcs in its sequential travel.

Further, it will be observed that the piston assembly is disposed immediately adjacent to the pressure-generating arc 17 so that liquid frictional losses are held to a minimum through the several passages. In addition, it will be observed that the piston assembly is operated by operation of the operating rod 19 and thereby entails no additional complicating driving mechanisms to effect operation of the piston structure.

The provision of such improved piston means results in improved performance during the interruption of line charging or capacitor currents since the liquid flow enters the arc region at the proper time. It also results in a flow of oil through the interrupting arc, as well as a circulating flow of oil through the pressure-generating arc.

The delayed pumping of the piston 35 results in the pressure-generating break 17 being established before operation of the piston. Consequently, even though the piston 35 may during a portion of its later travel be backed up by high arcing pressures, still the contacts 14, 15 will not be forced closed. In addition, it may be noted that the compression spring 20, which actuates the piston 35, is effective in accelerating the operating rod 19 prior to the start of pumping, thus getting a greater use-factor for the spring.

Although we have shown and described a specific structure, it is to be clearly understood that the same was merely for the purpose of illustration, and that changes and modifications may readily be made therein by those skilled in the art without departing from the spirit and scope of the appended claims.

We claim as our invention:

1. A circuit interrupter including a pressure-generating contact, an intermediate contact and an interrupting contact, the pressure-generating and intermediate contacts cooperating to establish a pressure-generating arc, the intermediate and interrupting contacts cooperating to establish an interrupting arc, an operating rod for actuating the pressure-generating contact, a piston chamber, a piston movable within the piston chamber and having its two sides exposed to the arcing pressure, passage means communicat-

ing the piston chamber on the working side thereof only with the pressure-generating arc, means biasing the operating rod in a direction to move liquid toward the pressure-generating arc, means interconnecting the operating rod with the piston, a member of relatively enlarged cross-sectional area movable with the operating rod and a member of relatively small cross-sectional area movable thereby, and the operating rod being movable through the piston chamber so that the enlarged member enters the piston chamber as the smaller member leaves the piston chamber so that a positive diminution of liquid takes place within the piston chamber.

15 2. A circuit interrupter including a pressure-generating contact, an intermediate contact and an interrupting contact, the pressure-generating and intermediate contacts cooperating to establish a pressure-generating arc, the intermediate and interrupting contacts cooperating to establish an interrupting arc, an operating rod for actuating the pressure-generating contact, a piston chamber, a piston movable within the piston chamber and having its two sides exposed to the arcing pressure, passage means communicating the piston chamber on the working side thereof only with the pressure-generating arc, means biasing the operating rod in a direction to move liquid toward the pressure-generating arc, means interconnecting the operating rod with the piston, a member of relatively enlarged cross-sectional area movable with the operating rod and a member of relatively small cross-sectional area movable thereby, the operating rod being movable through the piston chamber so that the enlarged member enters the piston chamber as the smaller member leaves the piston chamber so that a positive diminution of liquid takes place within the piston chamber, and the interconnecting means between the operating rod and the piston utilizing a lost-motion connection.

3. A circuit interrupter including a pressure-generating contact, an intermediate contact and an interrupting contact, the pressure-generating and intermediate contacts cooperating to establish a pressure-generating arc, the intermediate and interrupting contacts cooperating to establish an interrupting arc, an operating rod for actuating the pressure-generating contact, a piston chamber, a piston movable within the piston chamber and having its two sides exposed to the arcing pressure, passage means communicating the piston chamber on the working side thereof only with the pressure-generating arc, means biasing the operating rod in a direction to move liquid toward the pressure-generating arc, means interconnecting the operating rod with the piston, a member of relatively enlarged cross-sectional area movable with the operating rod and a member of relatively small cross-sectional area movable thereby, the operating rod being movable through the piston chamber so that the enlarged member enters the piston chamber as the smaller member leaves the piston chamber so that a positive diminution of liquid takes place within the piston chamber, means venting the interrupting arc, and second passage means interconnecting the pressure-generating arc with the interrupting arc.

70 4. A circuit interrupter including a pressure-generating contact, an intermediate contact and an interrupting contact, the pressure-generating and intermediate contacts cooperating to establish a pressure-generating arc, the intermediate and interrupting contacts cooperating to establish

lish an interrupting arc, an operating rod for actuating the pressure-generating contact, a piston chamber, a piston movable within the piston chamber and having its two sides exposed to the arcing pressure, passage means communicating the piston chamber on the working side thereof only with the pressure-generating arc, means biasing the operating rod in a direction to move liquid toward the pressure-generating arc, means interconnecting the operating rod with the piston, a member of relatively enlarged cross-sectional area movable with the operating rod and a member of relatively small cross-sectional area movable thereby, the operating rod being movable through the piston chamber so that the enlarged member enters the piston chamber as the smaller member leaves the piston chamber so that a positive diminution of liquid takes place within the piston chamber, the interconnecting means between the operating rod and the piston utilizing a lost-motion connection, means venting the interrupting arc, and second passage means interconnecting the pressure-generating arc with the interrupting arc.

5. A circuit interrupter of the liquid-break type including an arc-extinguishing unit, contact means for establishing an arc within the unit, an operating rod for actuating the contact means, a piston chamber, a piston movable within the piston chamber and having its two sides exposed

10
